UNITED STATES PATENT OFFICE.

FINLEY R. PORTER, OF PORT JEFFERSON, NEW YORK, ASSIGNOR TO FINLEY ROBERT-
SON PORTER COMPANY, INC., OF PORT JEFFERSON, NEW YORK, A CORPORATION OF
DELAWARE.

OIL-PUMP.

1,238,819.

Specification of Letters Patent. Patented Sept. 4, 1917.

Application filed November 22, 1916. Serial No. 132,818.

To all whom it may concern:

Be it known that I, FINLEY R. PORTER, a citizen of the United States, and resident of Port Jefferson, in the county of Suffolk 5 and State of New York, have invented a new and useful Improvement in Oil-Pumps, of which the following is a specification.

In actual practice it has been found very difficult, if not impossible, to successfully 10 produce a circulating oil pump for internal combustion engines which will work efficiently at both low and high engine speeds. When the pump has been designed especially for pumping oil at low engine speeds, it has 15 been found inefficient or inoperative to pump oil at high engine speeds and vice versa.

The object of my invention is to produce 20 an oil pump arranged to pump the oil efficiently at all speeds, means being provided for independently regulating the amount of 25 oil pumped to different points, whereby a certain point or certain points may receive a greater amount of oil than another point or other points as is essential in many of the uses for which the pump is designed.

The pump generally comprises coacting 30 reciprocating and rotary elements, the reciprocating elements serving to positively pump the oil at low speeds and the rotary element serving to pump the oil by centrifugal action at high speeds.

The pump more particularly comprises a 35 casing having axial inlet and peripheral outlets, in which casing a barrel rotates around the axial inlet, said barrel having two or more chambers therein arranged at different distances from and parallel to the axis of rotation of the barrel, said chambers having inlet and outlet ports arranged respectively 40 nearer to and farther away from the axis of rotation of the barrel, said inlet and outlet ports being brought into and out of communication with the axial inlet and peripheral outlets of the casing as the barrel is 45 rotated; plungers being located in said oil chambers and reciprocated as the barrel is rotated by two or more pairs of concentric upper and lower stationary cams having inclined parallel faces along which the opposite 50 ends of their respective plungers travel; means being employed to independently adjust each pair of upper and lower cams to change the stroke of the plunger or plungers operated thereby for regulating the amount 55 of oil pumped to different points.

A practical embodiment of my invention is represented in the accompanying drawings in which,

Figure 1 is a top plan view of the pump; 60 Fig. 2 is a side view,

Fig. 3 is a section taken in the plane of the line III—III of Fig. 1;

Fig. 4 is a horizontal section taken in the plane of the line IV—IV of Fig. 3;

Fig. 5 is a horizontal section taken in the 65 plane of the line V—V of Fig. 3;

Fig. 6 is a vertical section taken in the plane of the line VI—VI of Fig. 3, and

Fig. 7 is a vertical section taken in the 70 plane of the line VII—VII of Fig. 3.

The oil pump casing comprises the main portion 17, and the side extension 18. The main portion of the casing has a plurality of transversely arranged oil discharge ports 19 extending part way around the bore 20. 75 In the present instance, where the pump is designed for discharging oil to eight different sources, eight of these transversely arranged ports 19 are provided in eight different horizontal planes. A barrel 21 rotates 80 in the bore 20 of the casing intermediate its top and bottom, which barrel is provided with an uprising shaft 22, by means of which the barrel may be rotated from any desired source of power, as, for instance, from the 85 engine, not shown, in connection with which the pump is to be used. This rotary barrel is supported in its position by providing the shaft 22 with a nut 23 which bears upon the cover 24 of the casing through which the 90 shaft 22 projects. This shaft 22 also has a bearing 25 in the cap 26 of the cover 24. The rotary barrel 21 has a central bore 27 opening through its bottom, into which bore is introduced an open-ended tube 28 projecting 95 upwardly from a plate 29 which closes the bottom of the bore 20 of the casing.

A ring 30 screwed into the bottom of the bore 20, serves to hold the plate 29 and its tube 28 in position. 100

A suitable oil screen 31 is interposed between the plate 29 and ring 30. Pairs of concentric upper and lower stationary cam rings are introduced into the bore, 20, above and below the rotary barrel 21. In the 105 present instance, I have shown two pairs of these upper and lower cam rings. The upper outer cam ring 32 is provided with diametrically opposed hollow trunnions 33, 34, mounted to turn in the casing 17, the hollow 110

trunnion 34 being provided within the extension 18, with a gear 35. The upper inner cam ring 36 is provided with two diametrically opposed trunnions 37, 38, mounted to turn in the hollow trunnions 33, 34, the trunnion 38 projecting beyond the trunnion 34, and being provided with a gear 39 within the casing extension 18. The lower outer cam ring 40 is provided with diametrically opposed hollow trunnions 41, 42, mounted to turn in the casing 17, the trunnion 42 being provided with a gear 43 within the extension 18. The lower inner cam ring 44 is provided with diametrically opposed trunnions 45, 46, mounted to turn in the hollow trunnions 41, 42, the trunnion 46 projecting beyond the trunnion 42, and being provided with a gear 47 within the casing extension 18.

20 The outer and inner pairs of upper and lower concentric cam rings are rocked independently by two shafts 48, 49, respectively, the shaft 48 being provided with gears 50, 51, meshing with the gears 35 and 43 respectively, and the shaft 49 being provided with gears 52, 53, meshing with the gears 39, 47 respectively. The shafts 48, 49, are mounted in suitable bearings in the casing extension and project upwardly through the cover 24, in position where they may be turned by a key or other suitable operating device.

These pairs of upper and lower cam rings are provided with parallel inclined inner faces for engaging the opposite ends of their respective pump plungers, which pump plungers are mounted to reciprocate in oil chambers arranged at different distances from and parallel to the axis of rotation of the barrel 21. In the present instance, I have shown eight of these oil chambers and their respective plungers, four of these chambers 54, being so arranged that their plungers 55 will be operated by the inclined parallel faces of the upper and lower cam rings 32, 40 of the outer pair, and four chambers 56 being so arranged that their plungers 57 will be operated by the parallel inclined faces of the inner pair of the upper and lower cam rings 36, 44. Each of the outer oil chambers 54 has an inlet port 58 and an outlet port 59, arranged to be brought into communication with the vertically elongated port 60 in the side wall of the axially arranged inlet tube 28 and its transversely arranged outlet port 19 respectively of the casing as the barrel is rotated. Similarly, each of the inner oil chambers 56 has an inlet port 61 and an outlet port 62, arranged to be brought into communication with the vertically elongated port 60 of the axial inlet tube 28 and its transversely arranged outlet port 19, respectively of the casing as the barrel is rotated.

It is understood that each one of these

of its oil chamber and projecting into engagement with the inclined face of the lower cam ring and a reduced stem projecting upwardly through the barrel into engagement with the upper cam ring, leaving an oil space in the chamber above the head of the plunger, to which the oil is supplied and from which it is discharged during the operation of the pump.

In the operation of the pump it will be understood that the strokes of the two sets of plungers can be independently adjusted by the rocking of the pairs of upper and lower cam rings so that the amount of oil pumped to different points can be independently regulated and at the same time the amount of oil pumped to all of the different points can be regulated, the rocking of the cams in one direction serving to increase the strokes of the plungers to increase the supply of oil and the rocking of the cams in the other direction serving to decrease the strokes of the plungers and consequently decrease the amount of oil pumped thereby.

It is evident that the means which I have disclosed for varying the strokes of the plungers is only one of the many embodiments which I may employ for this purpose, and it is also obvious that the pump may be adapted for discharging any number of streams of oil.

In operation, when the pump is being driven at low speeds, as, for instance, at a low engine speed, the oil will be drawn into and forced from the pump positively by the reciprocation of the plungers. When the pump is driven at high speeds, as, for instance, at a high engine speed, the rotary movement of the barrel, together with the relative locations of the inlet and outlet ports respectively nearer to and farther away from the axis of rotation of the barrel, will cause the oil to be drawn into and forced from the bore by centrifugal action, thus insuring an ample supply of oil at high speeds as well as at low speeds by this combined centrifugal and positive action of the pump.

It is evident that various changes may be resorted to in the construction, form and arrangement of the various parts without departing from the spirit and scope of my invention, and hence I do not wish to limit myself strictly to the construction herein shown and described, but

What I claim is:

1. In an oil pump, means to pump the oil to different points positively at low speeds and by centrifugal action at high speeds, and means for independently regulating the amount of oil pumped to said different points.

2. In an oil pump, means to pump the oil to different points positively at low speeds, means to pump the oil to said different points

- by centrifugal action at high speeds and means for independently regulating the amount of oil pumped to said different points.
5. 3. In an oil pump, reciprocating means to pump the oil to different points positively at low speeds, means to pump the oil to said different points by centrifugal action at high speeds, and means for independently regulating the amount of oil pumped to said different points.
10. 4. In an oil pump, means to pump the oil to different points positively at low speeds, rotary means to pump the oil to said different points by centrifugal action at high speeds, and means for independently regulating the amount of oil pumped to said different points.
15. 5. In an oil pump, reciprocating means to pump the oil to different points positively at low speeds, rotary means to pump the oil to said different points by centrifugal action at high speeds, and means for independently regulating the amount of oil pumped to said different points.
20. 6. In an oil pump, a plurality of reciprocating elements and a rotary element coacting to pump the oil to different points positively at low speeds and by centrifugal action at high speeds, the strokes of different reciprocating elements being independently changeable for regulating the amount of oil pumped.
25. 7. In an oil pump, a plurality of reciprocating elements and a rotary element coacting to pump the oil to different points positively at low speeds and by centrifugal action at high speeds, and adjusting means for independently changing the strokes of different reciprocating elements to regulate the amount of oil pumped.
30. 8. In an oil pump, a plurality of reciprocating plungers and a rotary barrel in which the plungers reciprocate, coacting to pump the oil to different points positively at low speeds and by centrifugal action at high speeds, the strokes of different plungers being independently changeable for regulating the amount of oil pumped.
35. 9. In an oil pump, a plurality of reciprocating plungers and a rotary barrel in which the plungers reciprocate, coacting to pump the oil to different points positively at low speeds and by centrifugal action at high speeds, and adjusting means for independently changing the strokes of different plungers to regulate the amount of oil pumped.
40. 10. In an oil pump, a rotary barrel having a plurality of oil chambers with inlet and outlet ports arranged respectively nearer to and farther away from the axis of rotation, plungers reciprocating in said chambers, whereby the oil is pumped to different points positively at low speeds by the reciprocation of the plungers and is pumped by centrifugal action at high speeds by the rotary movement of the barrel, and adjusting means for independently changing the strokes of different plungers to regulate the amount of oil pumped.
45. 11. In an oil pump, a casing having an axial inlet and peripheral outlets, a barrel rotating in said casing having oil chambers with inlet and outlet ports arranged to be brought into and out of communication with the casing inlet and outlets by the rotary movement of the barrel, plungers reciprocating in said chambers, whereby the oil is pumped to different points positively at low speeds and by centrifugal action at high speeds, and adjusting means for independently changing the strokes of different plungers to regulate the amount of oil pumped.
50. 12. In an oil pump, a plurality of reciprocating plungers, a rotary barrel in which the plungers reciprocate, coacting to pump the oil to different points positively at low speeds and by centrifugal action at high speeds, and pairs of upper and lower adjustable cam rings having parallel inner faces engaging the upper and lower ends of different plungers to reciprocate them for regulating the amount of oil pumped.
55. 13. In an oil pump, a plurality of reciprocating plungers, a rotary barrel in which the plungers reciprocate, coacting to pump the oil to different points positively at low speeds and by centrifugal action at high speeds, and independently adjustable pairs of upper and lower cam rings having parallel inner faces engaging the upper and lower ends of different plungers to reciprocate them for regulating the amount of oil pumped.
60. 14. In an oil pump, a plurality of reciprocating plungers, a rotary barrel in which the plungers reciprocate, coacting to pump the oil to different points positively at low speeds and by centrifugal action at high speeds, pairs of upper and lower cam rings having parallel inner faces engaging the upper and lower ends of different plungers to reciprocate them, and adjustable means for independently rocking each pair of cam rings to change the strokes of the plungers for regulating the amount of oil pumped.
65. In testimony, that I claim the foregoing as my invention, I have signed my name this 10th day of November, 1916.
70. FINLEY R. PORTER.
